RAILWAY SWITCH OPERATING APPARATUS

Herbert L. Bone, Forest Hills, Pa., assignor to
The Union Switch & Signal Company, Swiss-
vale, Pa., a corporation of Pennsylvania

Application November 19, 1936, Serial No. 111,641

37 Claims. (Cl. 246—291)

My invention relates to railway switch operating apparatus, and particularly to apparatus for operating switches of the type which are adapted to be trailed. One object of my invention is to provide means for biasing the movable rails of a spring switch to one extreme position in such manner that when a train trails the switch and displaces the movable rails from such one extreme position, the biasing means will become effective to urge the movable rails to their opposite extreme positions until after the train has completely passed the switch, whereupon the biasing means will again become effective to bias the movable rails to such one extreme position.

Other objects of my invention will appear as the description proceeds.

I will describe one form of apparatus embodying my invention, and will then point out the novel features thereof in claims.

In the accompanying drawings, Fig. 1 is a top plan view, partly cross sectioned, showing a spring switch A provided with one form of switch operating apparatus embodying my invention. Fig. 2 is an enlarged top plan view of the biasing mechanism D shown in Fig. 1, the cover 25^b and a portion of the mechanism being removed to better illustrate the construction of the remainder of the mechanism. Figs. 3 and 4 are sectional views taken substantially on the lines III—III and IV—IV, respectively, of Fig. 2. Fig. 5 is a top plan view similar to Fig. 2 showing the position of the parts of the biasing mechanism D when the switch is moved from its normal position to a reverse position by a trailing train. Figs. 6 and 7 are diagrammatic views showing the resultant force which is exerted on the switch points by the spring connecting rod and biasing mechanism D during various operating conditions. Fig. 8 is a view similar to Fig. 2 showing a modified form of biasing mechanism which may be used in place of the mechanism D shown in Fig. 2. Fig. 9 is a top plan view showing a switch A provided with another form of switch operating apparatus embodying my invention. Fig. 10 is an enlarged top plan view of the biasing mechanism D¹ shown in Fig. 9.

Similar reference characters refer to similar parts in each of the several views.

Referring first to Fig. 1, the reference character A designates a railway switch, and the reference character B designates a device for operating the switch A. The switch A comprises, as usual, two fixed rails 1 and 1^a and two movable rails or switch points 2 and 2^a, the switch points being connected together adjacent their tips by a

head rod 3. When the switch occupies its normal position, in which position it is shown in Fig. 1, the movable rail 2^a engages the fixed rail 1^a and the movable rail 2 is spaced a slight distance from the fixed rail 1. When the switch is reversed, however, the movable rail 2 then engages the fixed rail 1 and the movable rail 2^a is spaced from the fixed rail 1^a.

The operating device B, as here shown, comprises a switch stand 5 having its base 5^a spiked or otherwise secured to the ties adjacent the switch A. A gear shaft 6 is journaled in the switch stand and carries a crank 7 and a gear segment 8. The gear segment 8 meshes with a pinion gear 9 keyed to a pinion shaft 10. The pinion shaft 10 extends through the side of the switch stand 5 and has attached to its outer end the usual weighted switch throwing lever 11.

The crank 7 of the switch throwing device B is connected with the head rod 3 of switch A by means of a link 12 and a spring connecting rod C. The spring connecting rod C may have any suitable form, but in the well-known form here shown, this connecting rod comprises a cylindrical housing 14 having a lateral extension 14^a fastened to the front rod 3. The left-hand end 14^b of the housing 14 has a smaller diameter than the body of the housing, while the right-hand end is threaded to receive a cap 15 having an end 15^a similar to the end 14^b. Slidably mounted in the opening in the end 14^b is a sleeve 16 provided with an annular flange 16^a located within the housing 14, and similarly mounted in the opening in the end 15^a is a sleeve 17 provided with an annular flange 17^a, located within the housing 14. A spring rod 13 extends through both sleeves 16 and 17 with sufficient clearance to permit the rod to slide freely in the sleeves, and this rod carries a compression spring 20 which engages the sleeves at the annular flanges 16^a and 17^a and urges the sleeves toward the positions in which the annular flanges 16^a of the sleeve 16 engage the shoulder formed on the inside of the housing 14 by the end 14^b, and the annular flange 17^a of the sleeve 17 engages the shoulder formed on the inside of the cap 15 by the end 15^a.

The spring rod 13 is provided with an annular shoulder 13^a for at times engaging the outer end of the sleeve 17 and with a nut 18 for at times engaging the outer end of the sleeve 16. The spring rod 13 is also provided with a nut 19 for locking the nut 18 in an adjusted position. The right-hand end of the spring rod 13 is pivotally attached to the link 12.

The apparatus thus far described is well-known

and its operation will be made clear as the description proceeds.

Associated with the switch A, the switch operating device B, and the spring connecting rod C is a biasing mechanism D embodying my present invention, which mechanism I will now describe. As best seen in Figs. 2 and 3, this mechanism in the form here illustrated comprises a casing 25, the base 25^a of which is secured, by means of bolts 26 or the like, to the same pair of cross ties 4 to which the switch operating device B is secured, on the side of the switch opposite to the device B, and the top of which is closed by a removable cover 25^b. Rotatably mounted within the casing 25 in aligned bearings 27 and 28, formed respectively in the base 25^a of the casing 25 and in a bearing bracket 29 which is secured by means of cap screws 30 to inwardly projecting lugs 25^c formed on opposite sides of the casing, is a crank 31 the lower end of which projects downwardly through the bottom of the casing and has fastened thereto, on the underside of the casing, an operating arm 32. The operating arm 32 is connected by means of a link 33 with the head rod 3 of the switch A in such manner that movement of the switch between its two extreme positions will cause rotation of the crank 31 between two extreme positions.

The toggle crank 31 is provided on the inside of the casing 25 with two pairs of vertically spaced oppositely extending arms, the lower pair of which 31^a and 31^b are formed integrally with the crank, and the upper pair of which 32^a and 32^b are removably secured to a square portion 31^c of the crank 31. The arms 31^a and 32^a are pivotally connected adjacent their outer ends with the enlarged head 34^a of a spring rod 34 forming part of a toggle spring unit S¹, and the arms 31^b and 32^b are pivotally connected adjacent their outer ends with a trunnion 35 forming part of a toggle spring unit S².

The toggle spring unit S¹ comprises, in addition to the spring rod 34, a trunnion 36 and a compressed coil spring 37. The trunnion 36 is pivotally mounted at its lower end in the bottom 25^a of the casing 25, and at its upper end in the bearing bracket 29, and is provided with a horizontally extending through hole which slidably receives the free end of the spring rod 34. The compressed coil spring 37 surrounds the spring rod 34 between its head 34^a and the trunnion 36 and acts, through the medium of the spring rod, to exert a force on the switch points which at times aids and at other times opposes that exerted on the switch by the spring 20 of the spring connecting rod C, as will be made clear hereinafter.

The toggle spring unit S² is similar to the toggle spring unit S¹ and comprises in addition to the trunnion 35, a spring rod 38 which is slidably mounted at one end in the trunnion 35, a stop nut 38^b, which is adjustably screwed onto one end of the spring rod, and a compressed coil spring 40 which surrounds the spring rod between its head 38^a and the trunnion 35, and which acts to constantly bias the spring rod to the position in which the nut 38^b engages the adjacent side of the trunnion.

The head 38^a of the spring rod 38 is pivotally connected with the short arm 39^a of a latch crank 39 forming part of an electromagnetic latch mechanism. The latch crank 39 is pivotally supported intermediate its ends on a pin 45 mounted in the base 25^a of the casing 25, and in the bearing bracket 29, and the long arm 39^b of this crank

is provided with a wedge-shaped latch dog 41, which, under certain conditions which will be made clear presently, cooperates with the beveled upper end of the armature 42 of an electromagnet M. The electromagnet M is secured to the side of the casing 25 by means of a bracket 43, and has its winding connected with the rails 1 and 1^a in series with a battery E in such manner that this magnet will become energized whenever a train occupies a track circuit which extends for 10 a short distance in both directions from the switch A. The armature 42 is biased by gravity to a lower position in which its beveled upper end is out of the path of movement of the latch dog 41, as shown in Figs. 3 and 4, but is arranged 15 to be moved, in response to the energization of the winding of the electromagnet, to an upper position in which its beveled upper end projects into the path of movement of the latch dog. It will be apparent, therefore, that when the magnet M is deenergized the latch arm is free to swing from a position on one side of the armature of the magnet to a position on the other side of the armature of the magnet, but that, when the magnet M is energized the latch arm is then 20 prevented from swinging past the position in which the latch dog engages the armature of the magnet. 25

The operation of the apparatus as a whole is as follows: The parts are so proportioned that 30 when the switch throwing lever 11 of the switch operating device B occupies its normal position in which it is shown on the drawings, a force will be transmitted to the switch points through the medium of the link 12, spring rod 13, nut 18, 35 sleeve 16, spring 20, housing 14, and head rod 3, which force will cause the spring 20 to become compressed and yieldably urge the switch points to their normal positions, but that, when the switch throwing lever 11 of the switch operating 40 device B is rotated from its normal position through an angle of substantially 180°, a force will then be exerted on the switch points through the medium of the link 12, spring rod 13, shoulder 13^a, sleeve 17, spring 20, and head rod 3, which 45 force will compress the spring 20 and cause it to bias the switch points 2 and 2^a to their reverse positions. The parts are further so proportioned that when the switch occupies any position between its mid stroke position and its normal position, the spring 37 of the biasing mechanism D will act through the spring rod 34, toggle crank 31, operating arm 32, link 33 and head rod 3 to exert a force on the switch points, which force urges them to their normal positions, but that, 50 when the switch points occupy any positions between their mid stroke positions and their reverse positions, the spring 37 of the spring unit S¹ will then act through the spring bolt 34, toggle crank 31, operating arm 32, link 33, and spring rod 3 55 to exert a force on the switch points, which urges the switch points toward their reverse positions. It will be apparent, therefore, that when the switch points are moved to either their normal or their reverse extreme positions by the switch 60 operating device B, the switch points will be biased to such extreme positions by both the spring 20 of the spring connecting rod C and by the spring 37 of the spring unit S¹. It will also be apparent that when the switch operating device B is operated to move the switch points from either extreme position to the other extreme position, the spring 37 of the toggle spring unit S¹ 65 will exert a force on the points which opposes their motion until the points have been moved 70 75

to their mid stroke positions, after which the spring 31 will then exert a force on the points which aids their motion. It will further be apparent that in order to avoid excessive deflection 5 of the spring 20 of the spring connecting rod C during movement of the switch points from either of their extreme positions to their other extreme positions, the parts will have to be so proportioned that the force exerted on the points 10 by the spring 20 at the beginning of their movement will be somewhat greater than the opposing force which is exerted on the points by the spring 31 of the toggle spring unit S¹. It will be understood, of course, that during movement of 15 the switch points from either extreme position to the other extreme position, the magnet M will be deenergized so that the latch arm 39 will be free to rotate past this magnet, and that as a result, the spring 40 of the toggle spring unit S² 20 will not exert any force on the switch points under these conditions.

I will now assume that the parts are all in their normal positions in which they are shown in the drawings, and that a vehicle trails the 25 switch. Under these conditions, as the wheels of the vehicle roll along the fixed rail 1^a, and the movable switch point 2, the switch points 2 and 2^a will be forced toward their reverse positions by the wheels, and since spring rod 13 of spring connecting rod C is now held stationary by virtue of its connection with the switch operating device B, spring 20 will become compressed and will exert an increased force on the switch points tending to restore them to their normal positions. 30

The movement of the switch points toward their reverse positions under these conditions will also cause the toggle crank 31 to rotate in a counter-clockwise direction, as viewed in Fig. 2, from its normal extreme position toward its reverse extreme position, and it will be apparent, therefore, that during the movement of the switch points to their mid stroke positions, the spring 31 of the toggle spring unit S¹ will exert a force 35 on the switch points which aids that exerted on the switch points by the spring 20 of the spring connecting rod C in tending to restore the switch points to their normal positions, but that, as soon as the switch points have been moved past their mid stroke positions, the spring 31 of the 40 toggle spring unit S¹ will then exert a force on the switch points which opposes that exerted on the points by the spring 20, and which assists in moving the points toward their reverse positions. It will also be apparent that during the movement 45 of the switch points toward their reverse positions the circuit for magnet M will be completed by the wheels and axles of the vehicle so that armature 42 of magnet M will occupy its attracted position, and that, as a result, as soon as the switch points have been moved a relatively short distance away from their normal positions, the force which is transmitted to the latch crank 39 through the medium of the toggle crank 31 and toggle spring unit S² will cause this 50 latch crank to rotate in a counterclockwise direction, as viewed in Fig. 2, to the position in which the latch dog 41 engages the upper end of the armature 42, as shown in Fig. 5. When the latch crank reaches this position, the point of 55 connection of the toggle spring unit S² with the latch crank will become a fixed fulcrum, and the spring 40 of the toggle spring unit S² will, therefore, act to exert a force on the switch points which opposes their movement until the toggle 60 crank formed by the toggle crank and spring unit S² has been moved past its dead center position, whereupon the spring 40 of the toggle spring unit S² will then act to exert a force on the switch points which opposes that due to the spring 20, and which assists that due to the spring 31 in 5 urging the points to their reverse positions. Due to the fact that the latch dog 41 does not engage the armature 42 until after the switch points have been moved away from their normal positions a slight distance by the trailing train, the 10 toggle formed by the toggle crank and spring unit S² will not reach its dead center position until the switch points have been moved a short distance beyond their midstroke positions, and it will be seen, therefore, that the spring 40 of the 15 toggle spring unit S² will not become effective to assist in moving the switch points to their reverse positions until the switch points have been moved some distance beyond the position in which the spring 31 of the toggle spring unit S¹ becomes 20 effective to assist in moving the switch points to their reverse positions. The stiffness of the springs 20, 31, and 40 are such, and the parts are so proportioned, that the force which is exerted on the points by the spring 20 during movement of the switch points to their reverse positions will always be greater than that exerted on the points by the spring 31, but that, the total force which is exerted on the switch points by the two springs 31 and 40 tending to urge the 30 points to their reverse positions after they have been moved to within a short distance of their reverse positions will exceed the opposing force due to the compressed spring 20, and will be sufficient to force the switch points 2 and 2^a to, 35 and hold them in, their full reverse positions. The positions which the parts of the biasing mechanism D occupy when the switch points have been moved to their full reverse positions, due to the train trailing the switch, are shown in Fig. 5. 40 The spring 40 of the toggle spring unit S² will continue to be effective to bias the switch points to their reverse positions as long as magnet M remains energized, and magnet M will remain energized under these conditions until after the 45 train has completely passed the switch. It will be seen, therefore, that while a train is trailing the switch there will be very little more wear on the switch points than there would be on the switch points of an ordinary switch, and very 50 much less wear than there would be on spring switches of the usual type equipped with the usual type oil buffer. As soon as magnet M becomes deenergized due to the train having passed out of the track circuit in which this magnet is included, the force holding the armature 42 in its attracted position will be removed, and the reaction of the spring 40 of the spring unit S² acting through the latch crank 39 will then force the armature 42 to its release position, thus allowing the latch crank to swing in a counter-clockwise direction past the position in which the latch dog 41 engages the armature 42, and hence releasing the load on the latch arm. The spring 60 40 will then expand until stop nut 38^b engages the trunnion 35. In this position of the parts the toggle spring 40 will no longer exert any effort on the switch points, and since the force exerted on the switch points by the spring 20 of 65 the spring connecting rod C tending to restore the switch points to their normal positions exceeds that exerted on the points by the spring 31 of the toggle spring unit S¹ tending to hold the switch points in their reverse positions, the 70 75

switch points will immediately start to return to their normal positions. During this return movement of the switch points the toggle crank 31 will be rotated in a clockwise direction, as viewed 55 in Fig. 2, and as a result, as soon as the switch points have passed their mid stroke positions, the spring 37 of the toggle spring unit S¹ will become effective to assist the spring 20 in restoring the points to their normal positions. The 10 clockwise rotation of the toggle crank will also cause the latch arm L to rotate in a counter-clockwise direction to one extreme position during the movement of the switch points to substantially their mid stroke positions and to then 15 rotate in a clockwise direction in such manner that when the switch points have been restored to their full normal positions the arm 39 will be restored to the position in which it is shown in Fig. 2. It should be noted that due to the location 20 of the pivotal connection of the toggle spring unit S² with the crank arm 39, the toggle crank swings further on the counterclockwise direction side of dead center than it does on the clockwise direction side. This disposition of the parts 25 makes it possible for the latch crank to be rotated to the position shown when the parts occupy their normal positions and to have the toggle spring unit S² exert a force tending to hold the switch in its reverse position when the switch 30 is moved from its normal position past its dead center position by a trailing train. The manner in which the resultant force which is exerted on the switch points by the three springs varies during movement of the switch points to their 35 reverse positions by the trailing train is shown by the curve 45 in Fig. 6, while the manner in which the resultant spring force which is exerted on the switch points during movement of the switch points to their normal positions from their reverse 40 positions after a train has trailed the switch varies is shown by the curve 46 in Fig. 6. These curves are believed to be self-explanatory and need not, therefore, be described in detail herein.

45 The biasing mechanism when the switch is moved to its reverse position by the switch operating device B is not arranged to provide the electric latch feature, and its resultant advantages of pushing the switch points toward their normal 50 positions farther than they are forced by a train trailing the switch. It is, however, possible to trail the switch from its reverse position without damage or without an undue amount of wear. The effective force on the switch points when the 55 switch is trailed from its reverse position to its normal position depends upon whether the magnet M is energized or deenergized during the trailing move, it being possible to provide contacts on the switch operating device B for deenergizing this magnet if it is desired that the magnet be deenergized. If the magnet M remains deenergized, the effective force which is exerted on the switch points will be due entirely to the 60 combined forces exerted on the points by the springs 37 and 20 and is represented by the curve 65 47 shown in Fig. 7. If the magnet M remains energized the latch crank will swing in a clockwise direction past the armature 42, thus forcing the armature downwardly as the latch dog passes 70 the armature and will then swing counterclockwise, as viewed in Fig. 2, until the latch dog engages the armature, the downward movement of the armature under these conditions being due to the shape of the engaging faces of the latch 75 dog and the armature. However, under these

conditions sufficient compression will not be developed in toggle spring S² to hold the switch points in their normal positions and the switch points will immediately start to return toward their reverse positions as soon as each pair of 5 wheels passes the points. However, as the switch points return toward their reverse positions the effort of spring 40 of toggle spring unit S² will increase, until when the switch points have been moved a predetermined distance away from their 10 normal positions, usually one inch, the total force exerted on the switch points by the two toggle springs and the spring 20 of the spring connecting rod C, will be in a direction to prevent further movement, as indicated by point a on curve 15 48 in Fig. 7. It follows, therefore, that the switch points will kick back and forth through a relatively short portion of the switch stroke as the train trails the switch, but inasmuch as the actual force on the switch points tending to move them toward their reverse positions will always be relatively small, the amount of wear which occurs on the switch points under these conditions will not be excessive. When the train has completely passed the switch and the magnet M has become 25 deenergized, the effort of toggle spring unit S² will then be removed and the switch will return to its reverse position. The forces which would be exerted on the switch points should the switch not be stopped at the point a during the trailing 30 movement are indicated by the portion of the curve 48 to the right of the point a. The switch points, however, would never move past the point a unless the mechanism was out of adjustment or was used on a switch which had inherently an unusually great tendency to return to its initially 35 set position.

The use of the spring unit S¹ in combination with the spring unit S² in the mechanism D in the manner previously described is desirable because it reduces to a minimum the force which must be exerted by the spring unit S² in order to force the switch points to, and hold them in, their full reverse positions while a train is trailing the switch, and hence reduces to a minimum 45 the size of the magnet M which must be provided with a given lever ratio between the two arms of the latch crank 39 in order to insure the proper functioning of the latch mechanism. It should be particularly pointed out, however, that by proportioning the parts in such manner that when the switch points are forced toward their reverse positions by a trailing train, the force which is then exerted on the switch points by the spring unit S² tending to move the points to their full reverse 50 positions will exceed the opposing force exerted on the switch points by the spring connecting rod, the use of the spring unit S¹ may be dispensed with. This construction is shown in Fig. 8. It is believed that the operation of the apparatus as a whole when this construction is employed will be understood from the foregoing and from an inspection of the drawings without further detailed description.

One advantage of the construction shown in Fig. 8 is that since this construction does not include the spring unit S¹, there is no opposing force on the switch points which must be overcome when the switch points are moved from either extreme position to the other extreme position by means of the switch operating device B.

Referring now to Fig. 9, I have here shown the switch A operatively connected with a modified form of biasing mechanism which is designated as a whole by the reference character D¹, and the 75

construction of which is such that the use of the switch operating device B and the spring connecting rod C shown in Fig. 1 are rendered unnecessary. The mechanism D¹ is illustrated in detail in Fig. 10, and as here shown, the arms 31^a and 32^a of the crank 31, instead of being disposed directly opposite the arms 31^b and 32^b as shown in Fig. 2, are spaced from the arms 31^b and 32^b by an obtuse angle, as measured in a counterclockwise direction, and are operatively connected with a spring unit S³, similar to the spring unit S¹, in such manner that the spring unit S³ will exert on the shaft 31 a force which biases the switch to its normal position in all positions of the switch, and which force is substantially the same in magnitude in both extreme positions of the switch. Furthermore, as here shown, the upper end of the shaft 31 is extended upwardly through the cover 25^b of the casing 25 and is provided on the outside of the casing with a squared portion 31^d which is adapted to receive a removable hand crank 46 whereby the switch may be at times manually operated from its normal to its reverse position in a manner which will appear presently. The remaining parts of the mechanism D¹ are similar to the corresponding parts of the mechanism D, and need not, therefore, be described in detail.

Associated with the mechanism D¹ is a normally open manually operable switch 47 which is connected in parallel with the rails 1 and 1^a in the control circuit for magnet M in such manner that when this switch is closed, the magnet M will become energized regardless of whether the rails 1 and 1^a are or are not occupied by a trailing train.

The operation as a whole of the apparatus shown in Fig. 9 is as follows: When the switch occupies its normal position in which it is shown in the drawings, it is held in this position by the force which is then exerted on it by the spring unit S³, and the parts are so proportioned that this force is sufficient to permit facing point movements over the switch with safety. When, however, the switch occupies its normal position and a train trails the switch, the spring unit S³ will continue to exert a force on the switch points tending to return them to their normal positions, but, under these conditions, the magnet M will be energized, and as a result, the movement of the switch points toward their reverse positions caused by the trailing train will cause the spring unit S² to exert on the switch points a force which opposes that due to the spring unit S³, and the parts are so proportioned that this force will exceed that due to the spring unit S³. It follows, therefore, that the switch points will be forced to, and held in, their reverse positions by the spring unit S² under these latter conditions as long as magnet M remains energized. Magnet M will, of course, remain energized until the train has completely passed the switch, whereupon it will become deenergized. When magnet M becomes deenergized, the spring unit S³ will then be effective to restore the switch points to their normal positions.

When it is desired to operate the switch to its reverse position by hand, the manually operable switch 47 is first closed, and the crank 31 is then rotated from the position in which it is shown in Fig. 10 to its opposite extreme position by means of the hand crank 46. This rotation will cause the switch to become biased to its reverse position in the same manner as when a train trails the switch, and after the switch has once become

biased to its reverse position it will then remain in this position until the contact 47 is subsequently opened at which time the switch will automatically return to its normal position.

If the switch is trailed after it has been manually operated to its reverse position, it will, of course, snap back to its normal position and remain there even though magnet M is energized when the train starts to trail the switch.

One advantage of apparatus embodying my invention is that inasmuch as the switch remains in its reverse position when it is moved to this position by a train trailing the switch until after the train has completely passed the switch, the train can stop and then reverse its direction without danger of splitting the switch.

Although I have herein shown and described only three forms of railway switch operating apparatus embodying my invention, it is understood that various changes and modifications may be made therein within the scope of the appended claims without departing from the spirit and scope of my invention.

Having thus described my invention, what I claim is:

1. The combination with a switch of the type adapted to be trailed, of electromagnetically controlled latch mechanism, means effective when a train trails said switch for energizing the electromagnet of said latch mechanism until after the train has completely passed said switch, and toggle mechanism operatively connected with said switch and with said latch mechanism and effective when the movable rails of said switch are displaced from their normal position by a train trailing said switch for biasing the rails to their opposite extreme position as long as the electromagnet of said latch mechanism remains energized.

2. The combination with a switch of the type adapted to be trailed, of an electromagnet, a circuit for said electromagnet including a source of current and the fixed rails of said switch in parallel, whereby when a train trails said switch said electromagnet will become energized, and spring means connected with said switch and controlled by said electromagnet and effective when a train trails said switch for biasing the movable rails of said switch to a position opposite to their initially set position and for subsequently retaining the movable rails in such opposite position as long as said electromagnet remains energized.

3. The combination with a switch of the type adapted to be trailed, of an electromagnet, means for energizing said electromagnet whenever a train trails said switch, latch mechanism controlled by said electromagnet, and a toggle spring operatively connected with said switch and with said latch mechanism in such manner that when said switch is displaced from an initially set position by a train trailing said switch said toggle spring will exert a force on said switch which urges said switch to a position opposite to its initially set position as long as said electromagnet remains energized.

4. The combination with a switch of the type adapted to be trailed, of an electromagnet, means for energizing said electromagnet whenever a train trails said switch, latch mechanism controlled by said electromagnet, and a toggle spring operatively connected with said switch and with said latch mechanism in such manner that when said switch is displaced from an initially set position by a train trailing said switch said toggle spring will exert a force on said switch which

urges said switch to and holds it in a position opposite to its initially set position as long as said electromagnet remains energized.

5. In combination, a railway switch of the type adapted to be trailed, a switch operating device movable between two extreme positions, resilient means for connecting said device with said switch normally effective to bias said switch to an extreme position corresponding to the position of 5 said operating device, electromagnetically controlled latch mechanism, means for energizing the electromagnet of said latch mechanism whenever a train trails said switch, and toggle spring mechanism connected with said switch and with said 10 latch mechanism and effective when said switch is displaced from one extreme position by a trailing train for exerting a force on said switch which opposes and exceeds that exerted on said switch by said resilient means.

15 6. In combination, a railway switch of the type adapted to be trailed, a switch operating device movable between two extreme positions, resilient means for connecting said device with said switch normally effective to bias said switch to an extreme position corresponding to the position of 15 said operating device, electromagnetically controlled latch mechanism, means for energizing the electromagnet of said latch mechanism whenever a train trails said switch, and toggle spring mechanism connected with said switch and with said latch mechanism and effective when said switch is displaced from one extreme position by a trailing train for exerting a force on said switch which opposes and exceeds that exerted on said switch by said resilient means as long as the electromagnet of said latch mechanism remains energized.

20 7. In combination, a railway switch of the type adapted to be trailed, a switch operating device 20 movable between two extreme positions, resilient means for connecting said device with said switch normally effective to bias said switch to an extreme position corresponding to the position of said device, a first toggle spring operatively connected with said switch in such manner that said switch is biased to its nearest extreme position by said first spring, an electromagnet, means for energizing said electromagnet whenever a train trails said switch, a latch crank, means controlled 25 by said electromagnet for limiting the movement of said latch crank when said electromagnet is energized, and a second toggle spring connected with said switch and with said latch crank and effective when a train trails said switch and displaces it from its one extreme position to exert 30 a force on said switch which opposes that due to said resilient means.

35 8. In combination, a railway switch of the type adapted to be trailed, a switch operating device 35 movable between two extreme positions, resilient means for connecting said device with said switch normally effective to bias said switch to an extreme position corresponding to the position of said device, a first toggle spring operatively connected with said switch in such manner that said switch is biased to its nearest extreme position by said first spring, an electromagnet, means for energizing said electromagnet whenever a train trails said switch, a latch crank, means controlled 40 by said electromagnet for limiting the movement of said latch crank when said electromagnet is energized, and a second toggle spring connected with said switch and with said latch crank in such manner that when a train trails said switch and displaces it from its one extreme position said 45

second toggle spring will exert a force on said switch which opposes that due to said resilient means, which force together with the force exerted on said switch by said first spring is sufficient to urge said switch to and hold it in its other extreme position as long as said electromagnet remains energized.

9. In combination, a railway switch of the type adapted to be trailed, a switch operating device movable between two extreme positions, 10 resilient means for connecting said device with said switch in such manner that said switch will normally be biased by said resilient means to an extreme position corresponding to the position of said device, a first toggle spring operatively 15 connected with said switch in such manner that said switch is biased to its nearest extreme position by said first spring by a force which is somewhat less than that normally exerted by said resilient means, an electromagnet, means for 20 energizing said electromagnet whenever a train trails said switch, a latch crank controlled by said electromagnet and prevented from moving past a predetermined position when said electromagnet is energized, and a second toggle spring connected 25 with said switch and with said latch crank in such manner that when a train trails said switch and displaces it from its one extreme position said latch crank will be moved to said predetermined position and said second toggle spring will 30 exert a force on said switch which opposes that due to said resilient means, and which force together with the force exerted on said switch by said first spring is sufficient to urge said switch to and hold it in its other extreme position as 35 long as said electromagnet remains energized.

10. In combination, a railway switch of the type adapted to be trailed, a switch operating device movable between two extreme positions, resilient means for connecting said device with said switch normally effective to bias said switch to an extreme position corresponding to the position of said device, a toggle crank operatively connected with said switch, a first toggle spring unit operatively connected with said toggle crank and effective to bias said switch to its nearest extreme position with a force which is somewhat less than that normally exerted on the switch by said resilient means, an electromagnet, means for energizing said electromagnet whenever a train trails said switch, an armature controlled by said electromagnet and movable to an attracted or a released position according as said electromagnet is energized or deenergized, a pivoted latch crank movable between two extreme positions, a latch dog secured to one arm of said crank and co-operating with said armature in such manner that said crank is prevented from rotating in one direction past a position intermediate its two extreme positions when said armature occupies its attracted position, and a second toggle spring unit operatively connected with said toggle crank and with the other arm of said latch crank in such manner that if said switch is displaced from its one extreme position by a trailing train the resultant movement of said toggle crank will cause said latch crank to rotate to its intermediate extreme position and will subsequently cause said second toggle spring unit to exert a force on said switch which opposes that due to said resilient means as long as said electromagnet remains energized.

11. In combination, a railway switch of the type adapted to be trailed, a switch operating device movable between two extreme positions.

- resilient means for connecting said device with said switch normally effective to bias said switch to an extreme position corresponding to the position of said device, a toggle crank operatively connected with said switch, a first toggle spring unit operatively connected with said toggle crank and effective to bias said switch to its nearest extreme position with a force which is somewhat less than that normally exerted on the switch by 5 said resilient means, an electromagnet, means for energizing said electromagnet whenever a train trails said switch, an armature controlled by said electromagnet and movable to an attracted or a released position according as said 10 electromagnet is energized or deenergized, a pivoted latch crank movable between two extreme positions, a latch dog secured to one arm of said crank and cooperating with said armature in such manner that said crank is prevented from 15 rotating in one direction past a position intermediate its two extreme positions when said armature occupies its attracted position, and a second toggle spring unit operatively connected with said toggle crank and with the other arm 20 of said latch crank in such manner that if said switch is displaced from its one extreme position by a trailing train the resultant movement of said toggle crank will cause said latch crank to rotate to its intermediate extreme position and will sub- 25sequently cause said second toggle spring unit to exert a force on said switch which opposes that due to said resilient means and which together with the force exerted on said switch by said first spring is sufficient to urge said switch to 30 and hold it in its other extreme position as long as said electromagnet remains energized. 35
12. In combination, a railway switch of the type adapted to be trailed, a switch operating device movable between two extreme positions; 40 resilient means for connecting said device with said switch in such manner that said switch is normally biased to an extreme position corresponding to the position of said operating device, an electromagnetic latch mechanism, means for 45 energizing the electromagnet of said latch mechanism whenever a train trails said switch, a toggle crank operatively connected with said switch, and a toggle spring unit connected with said toggle crank and with said latch mechanism in such 50 manner that if the switch is trailed away from one extreme position said toggle spring unit will act through said toggle crank to exert a force on said switch which opposes and exceeds that due to said resilient means. 55
13. In combination, a railway switch of the type adapted to be trailed, a toggle crank operatively connected with said switch, a first spring unit connected with said toggle crank and effective for constantly biasing said switch to one 60 extreme position, an electromagnetic latch mechanism, means for energizing the electromagnet of said latch mechanism whenever a train trails said switch, and a second spring unit connected with said toggle crank and with said latch mechanism in such 65 manner that when said switch is displaced from said one extreme position by a trailing train said second spring unit will exert a force on said switch which opposes that due to said first spring unit as long as the magnet of said latch mechanism remains energized. 70
14. In combination, a railway switch of the type adapted to be trailed, a toggle crank operatively connected with said switch, a first spring unit connected with said toggle crank and effec- 75
- tive for constantly biasing said switch to one extreme position, an electromagnetic latch mechanism, means for energizing the electromagnet of said latch mechanism whenever a train trails said switch, and a second spring unit connected with said toggle crank and with said latch mechanism in such manner that when said switch is displaced from said one extreme position by a trailing train said second spring unit will exert a force on said switch which opposes and exceeds that due to said first spring unit as long as the electromagnet of said latch mechanism remains energized. 5
15. In combination, a railway switch of the type adapted to be trailed, a toggle crank operatively connected with said switch, a first spring unit connected with said toggle crank and effective for constantly biasing said switch to one extreme position, an electromagnetic latch mechanism, a circuit for the magnet of said latch mechanism, including a source of current and the two fixed rails of said switch in parallel, and a second spring unit connected with said toggle crank and with said latch mechanism in such manner that when said switch is displaced from said one extreme position by a trailing train said second spring unit will exert a force on said switch which opposes that due to said first spring unit as long as the magnet of said latch mechanism remains energized. 10
16. In combination, a railway switch of the type adapted to be trailed, a toggle crank operatively connected with said switch, a first spring unit connected with said toggle crank and effective for constantly biasing said switch to one extreme position, an electromagnetic latch mechanism, a circuit for energizing the magnet of said latch mechanism whenever a train trails said switch, a second spring unit connected with said toggle crank and with said latch mechanism in such manner that when said switch is displaced from said one extreme position by a trailing train said second spring unit will exert a force on said switch which opposes that due to said first spring unit as long as the magnet of said latch mechanism remains energized. 15
17. A biasing mechanism comprising a toggle crank movable between two extreme positions, a first spring means connected with said toggle crank and effective to bias said toggle crank to its nearest extreme position, electromagnetic latch mechanism, and a second spring means connected with said toggle crank and with said latch mechanism and effective if said toggle crank is moved from its one extreme position to its other extreme position when the electromagnet of said latch mechanism is energized for exerting on said toggle crank a force which opposes that due to said first spring means. 20
18. A biasing mechanism comprising a toggle crank movable between two extreme positions, a first spring means connected with said toggle crank and effective to bias said toggle crank to its nearest extreme position, electromagnetic latch mechanism, and a second spring means connected with said toggle crank and with said latch mechanism and effective if said toggle crank is moved from its one extreme position to its other 25

- extreme position when the electromagnet of said latch mechanism is energized for exerting on said toggle crank a force which opposes and exceeds that due to said first spring means.
19. A biasing mechanism comprising a toggle crank movable between two extreme positions, a first spring means connected with said toggle crank and effective to bias said toggle crank to its nearest extreme position, electromagnetic latch mechanism, and a second spring means connected with said toggle crank and with said latch mechanism and effective if said toggle crank is moved from its one extreme position to its other extreme position when the electromagnet of said latch mechanism is energized for exerting on said toggle crank a force which opposes that due to said first spring means as long as said latch mechanism subsequently remains energized.
20. A biasing mechanism comprising a toggle crank movable between two extreme positions, a first spring means connected with said toggle crank and effective to bias said toggle crank to its nearest extreme position, electromagnetic latch mechanism, and a second spring means connected with said toggle crank and with said latch mechanism and effective if said toggle crank is moved from its one extreme position to its other extreme position when the electromagnet of said latch mechanism is energized for exerting on said toggle crank a force which opposes and exceeds that due to said first spring means as long as the electromagnet of said latch mechanism subsequently remains energized.
21. A biasing mechanism comprising a toggle crank movable between two extreme positions, a first spring means operatively connected with said toggle crank and effective to bias said toggle crank to its nearest extreme position, a pivoted latch crank movable between two extreme positions, an electromagnet cooperating with said latch crank and effective when energized for preventing said latch crank from moving past a predetermined position intermediate its two extreme positions, and a second spring means operatively connected with said toggle crank and said latch crank in such manner that if said toggle crank is rotated from its one extreme position to its other extreme position when said electromagnet is energized said latch crank will be rotated to said predetermined position and said second spring means will become effective to exert a force on said toggle crank which opposes that due to said first spring means.
22. A biasing mechanism comprising a toggle crank movable between two extreme positions, a first spring means operatively connected with said toggle crank and effective to bias said toggle crank to its nearest extreme position, a pivoted latch crank movable between two extreme positions, an electromagnet cooperating with said latch crank and effective when energized for preventing said latch crank from moving past a predetermined position intermediate its two extreme positions, and a second spring means operatively connected with said toggle crank and said latch crank in such manner that if said toggle crank is rotated from its one extreme position to its other extreme position when said electromagnet is energized said latch crank will be rotated to said predetermined position and said second spring means will become effective to exert a force on said toggle crank which opposes and exceeds that due to said first spring means.
23. A biasing mechanism comprising a toggle crank movable between two extreme positions, a first spring means connected with said toggle crank and effective to bias said toggle crank to its nearest extreme position, a pivoted latch crank movable between two extreme positions, an electromagnet cooperating with said latch crank and effective when energized for preventing said latch crank from rotating past a predetermined position intermediate its two extreme positions, and a second spring means operatively connected with said toggle crank and said latch crank, the parts being so proportioned that when said toggle crank occupies either extreme position said second spring means will not exert any force on said toggle crank but that when said toggle crank is rotated from its one extreme position to its other extreme position when said electromagnet is energized said latch crank will be rotated to said predetermined position and said second spring means will then be effective to exert a force on said toggle crank which opposes that due to said first spring means.
24. A biasing mechanism comprising a toggle crank movable between two extreme positions, a first spring means operatively connected with said toggle crank and effective to bias said toggle crank to its nearest extreme position, a pivoted latch crank movable between two extreme positions, an electromagnet cooperating with said latch crank and effective when energized for preventing said latch crank from rotating past a predetermined position intermediate its two extreme positions, and a second spring means operatively connected with said toggle crank and said latch crank, the parts being so proportioned that when said toggle crank occupies either extreme position said second spring means will not exert any force on said toggle crank but that when said toggle crank is rotated from its one extreme position to its other extreme position and said electromagnet is energized said latch crank will be rotated to said predetermined position and said second spring means will then be effective to exert a force on said toggle crank which opposes and exceeds that due to said first spring means.
25. A biasing mechanism comprising a toggle crank movable between two extreme positions, a first spring means connected with said toggle crank and effective to bias said toggle crank to one extreme position, electromagnetic latch mechanism, and a second spring means connected with said toggle crank and with said latch mechanism and effective if said toggle crank is moved from its one extreme position to its other extreme position when the electromagnet of said latch mechanism is energized for exerting on said toggle crank a force which opposes that due to said first spring means.
26. A biasing mechanism comprising a toggle crank movable between two extreme positions, a first spring means connected with said toggle crank and effective to bias said toggle crank to one extreme position, electromagnetic latch mechanism, and a second spring means connected with said toggle crank and with said latch mechanism and effective if said toggle crank is moved from its one extreme position to its other extreme position when the electromagnet of said latch mechanism is energized for exerting on said toggle crank a force which opposes and exceeds that due to said first spring means.
27. A biasing mechanism comprising a toggle crank movable between two extreme positions, a first spring means connected with said toggle crank and effective to bias said toggle crank to

one extreme position, electromagnetic latch mechanism, and a second spring means connected with said toggle crank and with said latch mechanism and effective if said toggle crank is moved from its one extreme position to its other extreme position when the electromagnet of said latch mechanism is energized for exerting on said toggle crank a force which opposes that due to said first spring means as long as the electromagnet of said latch mechanism subsequently remains energized.

28. A biasing mechanism comprising a toggle crank movable between two extreme positions, a first spring means connected with said toggle crank and effective to bias said toggle crank to one extreme position, electromagnetic latch mechanism, and a second spring means connected with said toggle crank and with said latch mechanism and effective if said toggle crank is moved from its one extreme position to its other extreme position when the electromagnet of said latch mechanism is energized for exerting on said toggle crank a force which opposes and exceeds that due to said first spring means as long as the electromagnet of said latch mechanism subsequently remains energized.

29. A biasing mechanism comprising a toggle crank movable between two extreme positions, a first spring means operatively connected with said toggle crank and effective to bias said toggle crank to one extreme position, a pivoted latch crank movable between two extreme positions, an electromagnet cooperating with said latch crank and effective when energized for preventing said latch crank from rotating past a predetermined position intermediate its two extreme positions, and a second spring means operatively connected with said toggle crank and said latch crank in such manner that if said toggle crank is rotated from its one extreme position to its other extreme position when said electromagnet is energized said latch crank will be rotated to said predetermined position and said second spring means will become effective to exert a force on said toggle crank which opposes that due to said first spring means.

30. A biasing mechanism comprising a toggle crank movable between two extreme positions, a first spring means operatively connected with said toggle crank and effective to bias said toggle crank to one extreme position, a pivoted latch crank movable between two extreme positions, an electromagnet cooperating with said latch crank and effective when energized for preventing said latch crank from rotating past a predetermined position intermediate its two extreme positions, and a second spring means operatively connected with said toggle crank and said latch crank in such manner that if said toggle crank is rotated from its one extreme position to its other extreme position when said electromagnet is energized said latch crank will be rotated to said predetermined position and said second spring means will become effective to exert a force on said toggle crank which opposes and exceeds that due to said first spring means.

31. A biasing mechanism comprising a toggle crank movable between two extreme positions, a first spring means operatively connected with said toggle crank and effective to bias said toggle crank to one extreme position, a pivoted latch crank movable between two extreme positions, an electromagnet cooperating with said latch crank and effective when energized for preventing said latch crank from rotating past a predetermined

position intermediate its two extreme positions, and a second spring means operatively connected with said toggle crank and said latch crank, the parts being so proportioned that when said toggle crank occupies either extreme position said second spring means will not exert any force on said toggle crank but that if said toggle crank is rotated from its one extreme position to its other extreme position when said electromagnet is energized said latch crank will be rotated to said predetermined position and said second spring means will then become effective to exert a force on said toggle crank which opposes that due to said first spring means.

32. A biasing mechanism comprising a toggle crank movable between two extreme positions, electromagnetic latch mechanism, and spring means connected with said latch mechanism and with said toggle crank in such manner that when the electromagnet of said latch mechanism is de-energized said spring means is ineffective to exert any force on said toggle crank but that if said toggle crank is rotated from its one extreme position to its other extreme position when the electromagnet of said latch mechanism is energized said spring means will then become effective to bias said toggle crank to its other extreme position as long as the electromagnet of said latch mechanism subsequently remains energized.

33. The combination with a switch of the type adapted to be trailed, of means for normally biasing said switch to one extreme position, latch mechanism, spring means operatively connected with said latch mechanism and with said switch and effective when said switch is moved from one extreme position to the other for exerting a force on said switch which biases said switch to its other extreme position if said latch mechanism is then latched in a predetermined position, and means for at times latching said latch mechanism in said predetermined position.

34. The combination with a switch of the type adapted to be trailed, of means for normally biasing said switch to one extreme position, latch mechanism, spring means operatively connected with said latch mechanism and with said switch and effective when said switch is moved from one extreme position to the other for exerting a force on said switch which biases said switch to its other extreme position if said latch mechanism is then latched in a predetermined position, and means for latching said latch mechanism in said predetermined position when a train trails said switch.

35. The combination with a switch of the type adapted to be trailed, of means for normally biasing said switch to one extreme position, an electromagnet, means connected with said switch and controlled by said electromagnet for biasing said switch to its other extreme position if said switch is moved to its other extreme position when said electromagnet is energized, and means for energizing said electromagnet whenever a train trails said switch.

36. The combination with a switch of the type adapted to be trailed, of means for normally biasing said switch to one extreme position, an electromagnet, means connected with said switch and controlled by said electromagnet and effective for exerting a force on said switch which opposes that due to said biasing means if said switch is moved to its other extreme position when said electromagnet is energized, and means for energizing said electromagnet whenever a train trails said switch.

37. The combination with a switch of the type adapted to be trialed, of means for normally biasing said switch to one extreme position, an electromagnet, means connected with said switch and controlled by said electromagnet and effective for exerting a force on said switch which

opposes and exceeds that due to said biasing means if said switch is moved to its other extreme position when said electromagnet is energized, and means for energizing said electromagnet whenever a train trails said switch.

HERBERT L. BONE.
